UNITED STATES PATENT OFFICE.

WILLIAM F. MASTERS, OF STERLING, MASSACHUSETTS.

CLOTHES-WASHER.

1,231,631.

Specification of Letters Patent.

Patented July 3, 1917.

Application filed March 17, 1913. Serial No. 754,878.

To all whom it may concern:

Be it known that I, WILLIAM F. MASTERS, a citizen of the United States, residing at Sterling, in the county of Worcester and State of Massachusetts, have invented certain new and useful Improvements in Clothes-Washers, of which the following is a specification.

My invention relates to devices for washing clothes, said invention being designed as an improvement over a similar device conceived by me and described in an application dated Feb. 9, 1907, and bearing Serial #356,540.

15 As its primary object, the invention aims to provide improved valve means forming a part of what is commonly known as a "clothes pounder," which means, upon movement of the device in one direction is adapted to retain air under pressure therein and, upon movement of the device in another direction, break or partly break the vacuum formed therein during such movement.

The invention, as a further object, contemplates a structure wherein access may be had to the interior parts or walls of the device to permit, after continued use, the cleansing thereof, and the removal of accumulating substances such as dried soap and the like.

25 30 The above and additional objects are accomplished by such means as are illustrated in their preferred embodiment in the accompanying drawings, described in the following specification and then more particularly 35 pointed out in the claim which is appended hereto and forms a part of this application.

In describing my invention in detail reference will be had to the accompanying drawings wherein like characters denote like or 40 corresponding parts throughout the several views, and in which:—

Figure 1 is a side elevation of a clothes washer or pounder constructed in accordance with the present invention;

45 Fig. 2 is a fragmentary sectional view illustrating in detail the structure of the valve forming a part thereof;

Fig. 3 is an enlarged sectional view of the valve casing;

50 Fig. 4 is a similar view of the valve;

Fig. 5 is a similar view showing the manner in which the valve structure is connected to the shell or body of the device; and

55 Fig. 6 is a sectional view of a modified form of valve.

Referring now to the drawings by nu-

merals, 1 designates the shell or body of the device, which, in the present instance is substantially oval and to a certain extent frusto-conical. Uprights 2 are connected to the shell 1 by means of the frustum braces 3, the latter being secured to the said shell in any suitable manner, but preferably by soldering. A handle 4 connects the uprights 2, said handle having, as indicated at 5, 65 braces in engagement therewith. An additional brace designated 6 is soldered as at 7 to the uprights 2, said brace being arched to engage the handle 4 at a point 8 intermediate its ends.

The upper portion of the interior of the shell 1 is provided with a compartment 10 which is formed by a partition 11 extending across the shell. Said partition 11 is provided with a single opening 12 through which air, during a washing operation, is forced, the air being confined under pressure within the compartment 10. The top 13 of the shell 1 is provided with a central opening 14, said opening receiving a cup-shaped member 14' having a flange 15 disposed to overlap the edge of the opening and rest upon the upper surface of the said top to which it is soldered or otherwise secured. The cup 14' is also provided with an opening 16 which opening is aligned with the opening 12. Cup 14' is further provided with internal screw threads 17 which receive the external screw threads 18 upon one end of a valve casing 19. The valve casing 19 is cylindrical in form, having its lower end entirely open and its upper end partially closed, to in this manner form a constricted opening 20 aligned with openings 16 and 12 aforesaid. A metallic strip 21 is bent substantially in the shape of an inverted U, having, as illustrated to advantage in Fig. 3, its ends 22 soldered or otherwise suitably secured to the upper end of the casing. Said strip 21 being positioned directly over the opening 20 of the casing 19, it is apparent that a protector device is provided therefor.

Loosely disposed within the valve casing 19 is a closed end cylindrical valve 24. Said valve 24 being of less diameter, and shorter in length than the casing 19, the difference in size, as is obvious, will effect an air passage way between the inner wall of the casing and the outer wall of the valve.

In Fig. 6 of the drawings a modified form of the valve is shown, the said modified form consisting of a central portion 25 which has

annular flanges 26 and 27 formed upon its respective ends. Caps or other suitable end closures 28 and 29 provided with flanges 30 and 31 are secured to the central portion 25. 5 The opening 16' in the lower end of the cap 14' is of a size sufficiently large to permit the cap or closure 29 to extend therethrough so that the flange 31 of the same will rest upon the inner surface of the lower 10 end of the cap, while the opening 20' in the upper end of the valve casing 19' is of a diameter to permit the cap or closure 28 to extend therethrough so that the flange 30 will rest against the inner edge of the upper 15 end of the valve casing. In all other respects the modified form shown in Fig. 6 is the same as that previously described as the preferred form.

Operation is as follows:—The clothes 20 pounder is operated by giving it a rocking motion, this, by moving the handle alternately away from and toward the operator. As the pounder rests on that longitudinal edge of the shell which is next to the operator, and is rocked by the handle over toward the other longitudinal edge until the shell lies flat upon the clothes, the water, rushing with and through the clothes into the several compartments of the shell, compressing the air therein, the air passing 25 through the opening 12 and into the chamber 10 therefor. As long as the air is thus compressed, the valve member 24, by reason of its pressure therebeneath is forced 30 into the position indicated in Fig. 2 to close the opening 23 of the casing. A reverse movement of the shell will cause a vacuum to be formed therein and, as the air pressure exteriorly of the casing is greater than 35 the pressure within, the valve member 24 will automatically or by gravity fall from the position indicated in the said Fig. 2 to close the opening 16 of the cap. During 40 such fall, air is permitted to enter the interior of the shell through the casing 19 to 45 partially break the vacuum and in this manner provide for a second operation in the manner above set forth.

Copies of this patent may be obtained for five cents each, by addressing the "Commissioner of Patents, Washington, D. C."

From the foregoing, taken in connection with the accompanying drawings it is apparent that the air and water are forced through the clothes acted upon to in this manner thoroughly cleanse and wash the same; that the entire valve may be removed as well as the cap 14', thereby permitting the interior of the chamber 10 to be cleaned; and that by the automatic operation of the valve 24, the openings 23 and 16 are alternately opened and closed in a manner necessary to operation.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention; as defined in the appended claim.

Having thus fully described my invention, what I claim as new and desire to secure by Letters Patent, is:—

In a clothes pounder, the combination of a shell having a compartment formed therein at the top, said compartment being in communication with the lower portion of the shell, said shell having a valve casing, provided with an opening at either end, with one of said openings in communication with the compartment, and a valve reciprocable in said casing spaced from the sides thereof whereby during oscillation of the shell the valve will be oscillated automatically to alternately close the openings in the valve casing to alternately create and relieve the vacuum within the compartment.

In testimony whereof I affix my signature in presence of two witnesses.

WILLIAM F. MASTERS.
